UNITED STATES PATENT OFFICE.

GUST V. MALMSTROM, OF KANE, PENNSYLVANIA.

ICE-CREEPER.

1,160,425.

Specification of Letters Patent. Patented Nov. 16, 1915.

Application filed May 3, 1915. Serial No. 25,561.

To all whom it may concern:

Be it known that I, GUST V. MALMSTROM, a citizen of the United States, residing at Kane, in the county of McKean and State of Pennsylvania, have invented certain new and useful Improvements in Ice-Creepers; and I do declare the following to be a full, clear, and exact description of the invention, such as will enable others skilled in the art 10 to which it appertains to make and use the same.

This invention relates to improvements in ice creepers and more particularly to those permanently positioned on the heels of a 15 pair of shoes.

The objects of the invention is to provide a simply constructed and efficient device of this character, the spurs or prongs of which may be thrown back out of the way when 20 desired and completely housed within the shoe heel to prevent injury to the surface engaged by the shoe carrying them.

Another object is to provide a rubber heel shoe equipped with an ice creeper which 25 may be housed within the heel or projected for use as may be desired.

Another object is to provide improved means for holding said creeper in projected or retracted position.

With these and other objects in view, the 30 invention consists of certain novel features of construction, and the combination and arrangement of parts as will be more fully described and claimed.

In the accompanying drawings: Figure 1 35 represents a side elevation of the heel portion of a shoe, partly in section showing this improved creeper applied and arranged in inoperative position; Fig. 2 is a bottom plan view thereof; Fig. 3 is a side elevation of a shoe heel showing this improved creeper projected into operative position; Fig. 4 is a bottom plan view thereof.

In the embodiment illustrated, a shoe heel 40 H is shown constructed of leather or other suitable material and having a rubber heel R applied thereto, said rubber heel being secured by the usual fastening elements.

Arranged between the rubber heel R and 45 the leather heel H, is a plate 1 which is secured to the leather heel by suitable screws or other fastening elements and over which is mounted a spring retaining plate 2, here shown in the form of a spring metal strip secured at its opposite ends by screws 3 and

provided intermediately of its ends preferably midway its length with an outwardly bowed loop 4 for a purpose to be described.

Formed within the rubber heel R is a 60 recess 5 which may be of any suitable or desired configuration and the walls of which are beveled as shown at 6, said beveled wall recess being designed to prevent clogging or packing of snow therein.

Pivots mounted on the spring retaining member 2 is a spur carrying member 7 here shown in the form of a rectangular loop 8 having diverging arms 9 and 10 extending from two of the corners thereof, said arms being provided at their free ends 70 with spurs 11, preferably formed by pointing and bending the terminals of the arms in a plane at right angles to said arms so that when the member 7 is swung rearwardly into the position shown in Figs. 3 and 4, these spurs 11 will be positioned outwardly to form surface penetrating members which are designed to become embedded in the ice and prevent slipping of the person wearing the shoes 75 equipped therewith.

Two large headed screws 12 are shown 80 mounted in the heel R in position to engage and support the spur carrying ends of the arms 9 and 10 as is shown clearly in Fig. 4 which thus take the weight caused by the forcing of the spurs into the ice and prevent said spurs from becoming embedded in the rubber heel R.

The rectangular loop 8 of the member 7 85 is shown constructed of flat metal so that the end bar 13 thereof will be disposed flat against the plate 1 of the attachment, whether the creeper be arranged in operative or inoperative position as is shown clearly in the drawings, more especially in Figs. 1 and 3.

The spring plate 2 having the outwardly bowed loop 4, exerts its tension to hold the creeper either in operative or inoperative position so that when it is folded flat against the plate 1, all danger of the spur carrying 100 arms 9 and 10 falling accidentally downward and causing injury to polished floors, carpets and the like is avoided.

At the inner portion of the heel H are 105 formed two sockets 14 positioned to receive the spurs 11 when the member 7 is swung forwardly into inoperative position and whereby said spurs are amply protected and prevented from becoming injured or broken.

The walls of loop 4 are inclined in oppo- 110

site directions thereby adapting them to engage and hold the flat bar 13 yieldably in either of its folded positions.

I claim as my invention:

- 5 1. The combination with a shoe heel having a recess in the lower face thereof, of a resilient retaining member mounted therein, and a hingedly mounted spur carrying member having a flat strip engaged by said retaining member and serving as a fulcrum for said spur carrying member, said retaining member having an 'out-bowed' portion for receiving said strip and adapted to hold said spur carrying member in either operative or inoperative position.
- 10 2. The combination with a shoe heel having a recess in its lower face, of two superposed metal plates secured to said heel in said recess, the outer plate having an outwardly bowed transversely extending loop, and a spur carrying member having a transversely extending flat metal bar mounted for turning movement in said loop, the walls of said loop inclining in opposite directions and adapted to resiliently hold said bar in either of its two positions whereby the spurs are held in either operative or inoperative position.
- 15 3. The combination with a shoe heel having a recess in its lower face, of two superposed metal plates secured to said heel in said recess, the outer plate having an outwardly bowed transversely extending loop, and a rectangular loop having one member

engaged with the loop of said outer plate, 35 diverging arms extending from two of its opposite corners, said arms being provided at their free ends with laterally extending spurs, said heel having sockets positioned to receive said spurs when in inoperative position, and weight-resisting members positioned to support said spurs when in open operative position.

4. The combination with a shoe heel having a recess in its lower face, of two superposed metal plates secured to said heel in said recess, the outer plate having an outwardly bowed transversely extending loop, and a rectangular loop having one member 45 engaged with the loop of said outer plate, diverging arms extending from two of its opposite corners, said arms being provided at their free ends with laterally extending spurs, said heel having sockets positioned to receive said spurs when in inoperative 50 position, and weight-resisting members positioned to support said spurs when in open operative position, the recess in said heel having beveled edges to prevent the packing 55 of snow therein.

In testimony whereof I have hereunto set my hand in presence of two subscribing witnesses.

GUST V. MALMSTROM.
